UNITED STATES PATENT OFFICE.

EUGENE S. COOPER AND CHRIS BAKER, OF HAMMOND, INDIANA, ASSIGNEES TO AMERICAN STEEL FOUNDRIES, OF CHICAGO, ILLINOIS, A CORPORATION OF NEW JERSEY.

KING-POST FOR TRUSS BOLSTERS.

Application filed October 19, 1923. Serial No. 669,635.

To all whom it may concern:

Be it known that we, EUGENE S. COOPER and CHRIS BAKER, citizens of the United States, residing, respectively, at Hammond, 5 in the county of Lake and State of Indiana, and at Hammond, in the county of Lake and State of Indiana, have jointly invented certain new and useful Improvements in King-Posts for Truss Bolsters, of which the following is a specification.

This invention relates to a king post for a truss bolster.

One object of the invention is to provide a simple, relatively light but strong, durable 15 king post for a truss type of bolster.

Another object is to provide a cast king post structure which combines great vertical and transverse strength with light weight and ease of production and is adapted to meet the various requirements for successful commercial use.

These and other objects are accomplished by means of the arrangement disclosed on the accompanying sheet of drawings, in 25 which—

Figure 1 is a fragmentary elevational view of a truss bolster including our improved king post, the latter of which is shown in central vertical section;

Figure 2 is a transverse sectional view of said bolster showing the king post in side elevation;

Figure 3 is a front elevation of the king post;

Figure 4 is a top plan view thereof; and

Figure 5 is a sectional view of the king post taken in the plane of line 5—5 of Figure 2.

The various novel features of the invention will be apparent from the following description and drawings and will be particularly pointed out in the appended claims.

Referring to the figures of the drawings, it will be noted that we have illustrated our invention in connection with a truss type of bolster having a compression member 10 and a tension member 11. In this particular instance the compression member is of channel section, having a web 12 and vertically arranged flanges 13. The tension member 11 is shown as a single plate member. The king post occupies a central position between and spaces the tension and compression members and preferably comprises a

single casting including two adjacently arranged, yet slightly spaced, parallel tubes 14 which give great strength to the king post to withstand both vertical and transverse strains. These tubes 14 are connected at their ends by upper and lower flanges 15 and 16 to form bearing surfaces for the compression and tension members, respectively, the lower flanges 16 being made reentrant with respect to the tubes and upper flanges extending outwardly with respect thereto 55 for increasing the bearing surface, as best shown in Figures 1 and 5. While the oval shaped flange 15 is flat for cooperating with the flat web portion 12 of the compression member 10, the flange 16 is provided with a curved seat for the reception of the curved intermediate portion of the tension member 11. Intermediate the tubes 14 and at the upper ends thereof said tubes are connected by a hollow cylindrical portion 17 which extends downwardly about one-fifth the depth of the king post to form a bearing for the reception of a king pin, not shown, said tubes 14 intermediate their lengths being connected by a transverse flange 18 which forms a bracket for the support of the king pin. The upper end of the cylindrical portion 17 terminates in a plurality of oppositely arranged arc-shaped projections 19 which extend into an opening 20 in the 70 compression member for assisting in preventing relative movement between said compression member and king post.

It will be appreciated that if instead of providing the oppositely arranged or spaced 75 projections 19, a single continuous collar or annular projection were provided, the opening corresponding to the opening 20 in the compression member would, of necessity, have to be considerably larger, thereby 80 weakening the web of the compression member at that point. Furthermore, by avoiding the use of a large circular opening in the web 12 of the compression member and in place thereof providing an opening having 85 flattened sides 21, the flattened ends 22 of the projections 19 may engage said flattened sides 21 for assisting in preventing the king post from turning with respect to the compression member. At the same time, by reducing the width of the opening 20, or, in other words, in spacing the side walls 21 thereof just sufficiently to accommodate the 90

king pin, the size of the opening 20 is reduced to a minimum. The flattened sides 22 at the ends of the projections 19 lie along lines parallel to the longitudinal center of the bolster and are tangent to the circular inner walls of the opening in the cylindrical bearing portion 17.

In addition to the flanges and parts mentioned as connecting the tubes 14, various 10 flanges 23, 24 and 25 are provided for adding to the strength of the king post structure.

It is our intention to cover all modifications of the invention falling within the 15 spirit and scope of the following claims.

We claim:

1. A king post for a truss type of bolster, comprising a plurality of adjacently arranged tubes for resisting vertical and transverse strains and having directly associated therewith a hollow cylindrical portion for the reception of a king pin, said hollow cylindrical portion at one of its ends having a projection for cooperating with the bolster 20 compression member to prevent relative movement therebetween.

2. A king post for a truss type of bolster, comprising a plurality of adjacently arranged tubes for resisting vertical and transverse strains and having directly associated therewith a hollow cylindrical portion for the reception of a king pin, said hollow cylindrical portion having a plurality of spaced arcuate projections adapted to pass 30 into a non-circular opening in the associated compression member to prevent relative movement therebetween.

3. A king post for a truss type of bolster, comprising a plurality of adjacently arranged tubes for resisting vertical and transverse strains and having directly associated therewith a hollow cylindrical portion for the reception of a king pin, said hollow cylindrical portion having a plurality of spaced arcuate projections adapted 40 to pass into a non-circular opening in the associated compression member to prevent relative movement therebetween, and a flange connecting said tubes for supporting 50 a king pin.

4. A king post for a truss type of bolster, comprising a plurality of adjacently arranged tubes for resisting vertical and transverse strains and having directly associated therewith a hollow cylindrical portion for the reception of a king pin, and a flange connecting said tubes intermediate 55 the length thereof for supporting a king pin.

5. In combination with a compression member having an opening with flattened sides and a tension member, a king post interposed therebetween and comprising a cast member including a projection for extending into said compression member opening 60 and having a flattened surface for engaging

the flattened surface of said opening to prevent a relative turning movement between said king post and compression member.

6. In combination with a compression member having an opening with flattened 70 sides, and a tension member, a king post interposed between said tension and compression members and including a plurality of projections extending into said compression member opening and having flattened 75 portions for engaging the flattened sides of said opening to prevent relative rotary movement between said king post and compression member.

7. In combination with a compression 80 member having an opening with flattened sides and a tension member, a king post for spacing said tension and compression members and comprising a plurality of adjacently arranged parallel tubes for resisting vertical and transverse strains and having interposed therebetween a hollow cylindrical portion for the reception of a king pin, said hollow cylindrical portion having a plurality of projections extending into said 85 compression member opening and having flattened portions for cooperating with the flattened sides of said opening for preventing relative movement between said king post and said compression member. 90

8. A king post for a truss type of bolster, comprising a plurality of adjacently arranged tubes for resisting vertical and transverse strains, said tubes being connected at 100 one of their ends by flanges which are reentrant with respect to said tubes for increasing the bearing area.

9. A king post for a truss type of bolster, comprising a plurality of adjacently arranged tubes for resisting vertical and transverse strains, said tubes being connected at one of their ends by flanges which are reentrant with respect to said tubes and connected at their other ends by flanges which 105 extend outwardly with respect to said tubes 110 for increasing the bearing area. 110

10. A king post for a truss type of bolster, comprising a plurality of adjacently arranged tubes for resisting vertical and transverse strains, said tubes being connected at their lower ends by flanges which are reentrant with respect to said tubes and being connected at their upper ends by flanges which extend outwardly with respect 115 to said tubes for increasing the bearing area 120 for cooperating with the tension and compression members respectively of the bolster.

11. A king post for a truss type of bolster, comprising a plurality of adjacently arranged tubes for resisting vertical and transverse strains, and a flange in the form of a bracket connecting said tubes intermediate the length thereof upon which a king pin 125 may rest and be supported.

12. A king post for a truss type of bolster, 130

comprising a plurality of tubes arranged transversely of the bolster and along the transverse center line of said bolster for resisting vertical and transverse strains.

5 13. A king post for a truss type of bolster, comprising a plurality of flanged connected tubes arranged transversely of the bolster and along the transverse center line of said bolster for resisting vertical and transverse

10 strains.

14. A king post for a truss type of bolster, comprising a member having a plurality of tubular portions arranged transversely of the bolster and along the transverse center line of said bolster for resisting vertical and 15 transverse strains.

Signed at Hammond, Ind., this 13th day of October, 1923.
